UNITED STATES PATENT OFFICE.

ARTHUR W. NELSON, OF WILLIAMSPORT, PENNSYLVANIA, ASSIGNOR TO HERMANCE MACHINE COMPANY, OF WILLIAMSPORT, PENNSYLVANIA, A CORPORATION OF PENNSYLVANIA.

WOOD-PLANING MACHINE.

1,111,701.

Specification of Letters Patent.

Patented Sept. 22, 1914.

Application filed April 28, 1913. Serial No. 764,111.

To all whom it may concern:

Be it known that I, ARTHUR W. NELSON, a citizen of the United States of America, residing at Williamsport, in the county of 5 Lycoming and State of Pennsylvania, have invented certain new and useful Improvements in Wood-Planing Machines, of which the following is a specification, reference being had therein to the accompanying 10 drawings.

My invention relates to a planing machine and more particularly to that type of planing machine known as outside molder.

In constructions of outside molders now 15 in general use, it is quite customary to place the upper cutter head and the upper feed rolls on top of the main frame with the shafts or arbors that carry the cutter head and the feed rolls extending across the frame 20 from side to side, the cutter head and the rolls on the end of the shafts overhanging the bed or table. The lower feed rolls and the lower cutter head and side heads are mounted upon the table. With this type of 25 machine considerable difficulty has hereinbefore been encountered in properly driving the rolls and the cutter heads, without employing a complicated arrangement of belting. It is the object of my invention to so 30 arrange the parts that a simple arrangement of belting may be employed.

To this end the invention resides in the peculiar construction, arrangement and combination of parts as more fully hereinafter 35 set forth and claimed.

In the drawings,—Figure 1 is a plan view of a device embodying my invention; Fig. 2 is a side elevation thereof; and Fig. 3 is a section on the line $\alpha-\alpha$ of Fig. 1.

40 A designates the frame of the machine, of any suitable construction; B a vertical cutter head, and C an upper horizontally-arranged cutter head.

D E are the upper feed rolls and F G 45 the lower. The cutter head C is secured to the horizontally-arranged shaft H journaled in bearings I at opposite sides of the frame, while the member B is carried by a vertical shaft J, suitably journaled in bearings K.

50 L is the bed or table over which the work is fed and M is a shaft carrying the roll D, which constitutes the feed roll. This shaft extends completely across the frame and has fixed to an extension N thereof which pro-

jects beyond one side of the frame, a large 55 gear O that is driven from a pinion P upon a stub shaft Q. The pinion is rotatively fixed to a pulley Q' upon the shaft Q and this pulley is driven by means of a belt R from a pulley S on a shaft T and the latter 60 is rotated from the main drive shaft U by means of pulleys V W and belt X. The main drive shaft has a pulley Y secured thereto which directly drives the shaft J by a quarter-twist belt Z that connects the pulley Y and a pulley A' on the vertical shaft J. 65

B' is a belt forming the drive connection between a pulley C' on the shaft U and a pulley D' on the shaft H, the last-mentioned 70 pulleys being arranged as shown, within the sides of the frame. In order to have the shaft U best positioned for driving the various cutter heads and the other parts, it is desirable to arrange this shaft in relation to the various driven members, as shown in the 75 drawings, but when so positioned the plane of the upper portion of the belt B' would intersect the shaft E'. Therefore the shaft E' of the feed roll E is not extended completely across the frame but is journaled in 80 a bearing F' carried by a member G' that has the portion H' that extends across the belt arranged above the plane of the belt, so as not to interfere, as will be readily seen upon reference to Fig. 3. The shafts E' and M are connected to rotate at the same speed 85 preferably by a chain I' and sprockets K' L' respectively fixed to said shafts.

By the arrangement of parts hereinbefore described the cutter C is actuated by a 90 straight belt drive, and the cutter B by a quarter-turn belt drive, and both of these driving connections are directly from the main drive shaft U. Furthermore, the belt B' is arranged within the sides of the frame 95 and therefore, does not increase the width of the machine. Also the driving connection from the main belt drive and the gear O of the master feed roll shaft is carried by the frame.

100 What I claim as my invention is:—

1. In a planing machine, the combination 105 of a frame, a bed arranged at one side of the frame, a cutter head and a feed roll extending across the bed, a shaft for the cutter head journaled in bearings in the sides of the frame, a drive shaft, driving members respectively on the cutter head and the drive

shafts, each positioned intermediate the sides of the frame, a flexible connection between said driving members, a shaft for the feed roll arranged intermediate the shaft for the 5 cutter head and the drive shaft and extending transversely of the bed, a journal for said shaft to one side of said flexible connection and between the sides of the frame, and a member carrying said journal, mounted 10 upon the frame sides and having a portion arranged above the plane of the flexible connection.

2. In a planing machine, the combination 15 of a frame, of a horizontally-arranged bed positioned at one side of the frame, a cutter head and feed rolls extending across said bed, horizontal shafts for the cutter head and one of the feed rolls journaled in bearings in the sides of the frame and arranged 20 in substantially the same plane, a horizontal drive shaft extending transversely of and mounted upon the frame, pulleys upon said driving shaft and the cutter head shaft, arranged between the sides of the frame, a belt 25 connecting said pulleys, a shaft extending transversely of the bed for another of said feed rolls, a bearing in which said last-mentioned shaft is journaled, arranged in close proximity to the belt and in substantially the 30 same plane, a member carrying said bearing having the portion near said belt arranged in a plane above said belt, means for driving the first-mentioned feed roll shaft from the drive shaft, an actuating connection between 35 said feed roll shafts, a vertically-arranged cutter head positioned in operative relation to the bed, and a driving connection at one

side of the frame between said drive shaft and said vertical cutter head.

3. In a planing machine, the combination 40 of a frame, a bed arranged at one side of the frame, a cutter head and a feed roll extending across the bed, a shaft for the cutter head journaled in bearings in the sides of the frame, a drive shaft, driving members 45 respectively on the cutter head and the drive shafts, each positioned intermediate the sides of the frame, a flexible connection between said driving members, a shaft for the feed roll arranged intermediate the shaft for the 50 cutter head and the drive shaft and extending transversely of the bed, a second shaft for a second feed roll between the shafts for the drive shaft and the other of said feed rolls extending parallel to the other shaft of 55 said feed rolls, sprockets arranged upon said feed roll shafts intermediate the sides of the frame, an actuating connection between said sprockets, a bearing for said second shaft between its sprocket wheel and the 60 flexible connection between the driving members, a member extending between the sides of the frame carrying said bearing, said member having the portion extending across said flexible connection between the driving 65 members arranged above the plane of said connection.

In testimony whereof I affix my signature in presence of two witnesses.

ARTHUR W. NELSON.
